UNITED STATES PATENT OFFICE.

WALTER N. VANCE, OF CHICAGO HEIGHTS, ILLINOIS, ASSIGNEE, BY MESNE ASSIGNMENTS, TO LYON METAL PRODUCTS, INCORPORATED, OF AURORA, ILLINOIS, A CORPORATION OF ILLINOIS.

LOCKER.

Application filed December 10, 1925. Serial No. 74,582.

This invention relates in general to lockers and has for its object broadly the provision of a new and improved construction of locker, which may be conveniently employed to provide the necessary locker equipment for a given number of users, and which will require a minimum amount of floor space. Lockers embodying my invention contemplate in this regard the arrangement of individual coat and hat compartments of considerably less width than is ordinarily required and provided. Manifestly, a compartment for receiving suits, coats, or the like, need not be of great width, while those for the accommodation of hats, lunches, etc., must be relatively wide.

A further object of my invention is a construction of this character, wherein two compartments may be locked closed by a single locking device.

Another object of my invention resides in providing a so-called duplex locker, comprising a pair of side-by-side lower lockers and a pair of superimposed upper lockers, together with latching devices for the doors of each of said lockers, the latching means for the doors being arranged in sets including a selected upper and lower locker with a single shiftable means for latching and unlatching two doors of each set; and this construction further includes an arrangement whereby one of the doors of each set may be latched in the event that the other door of such set is already latched. And this arrangement also includes the construction whereby the means for operating the latching means for the doors of each set may comprise an operable handle for one of the doors.

Another important object is to provide such a device with a locking means that will be substantial and that may be cheaply manufactured.

Numerous other objects and advantages of the invention will be apparent as it is better understood from the following description, which, taken in connection with the accompanying drawings, discloses a preferred embodiment thereof.

Referring to the drawings:

Figure 1 is a front elevation of a device embodying my invention;

Fig. 2 is a section taken substantially on line 2-2 of Fig. 1;

Fig. 3 is a section taken substantially on line 3-3 of Fig. 2, showing more clearly the arrangement of the latching means as applied to the duplex locker.

Fig. 4 is a section taken substantially on line 4-4 of Fig. 3;

Fig. 5 is a section taken on line 5-5 of Fig. 3; and

Fig. 6 is a perspective view showing a portion of the interior of a locker and illustrating the operation of the latching devices.

To illustrate my invention, I have shown a locker body or enclosure 11, comprising angle iron frame members 12, wall plates 13, and hinged closures or doors 13^a, 14, 15 and 16. The frame members 12 and wall plates 13 may be made or formed as shown and may be of any suitable material and size and secured together in any suitable manner, such as by rivets or the like.

Sheet metal separating plates 17 are preferably provided to divide the enclosed space into a plurality of separate compartments of suitable size. The plates 17 may be secured in position in any suitable manner, such as by riveting to the frame members 12 or wall sheet 13, or both. The closures or doors 13^a, 14, 15 and 16 are preferably formed of sheet metal and may be secured to the frame members 12 in any suitable manner, such as by hinges, as indicated at 18.

In the embodiment of my invention illustrated, I have shown as one form thereof a so-called duplex locker, wherein the frame is divided so as to provide two lower lockers arranged side by side and relatively narrow, so as to accommodate coats and the like, and two upper compartments arranged over said lower compartments and arranged one over the other, said upper compartments extending preferably the full width of the locker and adapted to accommodate hats and wider objects if desired. By means of this arrangement, one person can use a particular lower locker and its corresponding upper locker, and another person can use the other lower locker and its corresponding upper locker, the latching means being particularly arranged so that one latching means serves to lock a lower door and an upper door, and

the other latching means serves to latch the other lower door and the other upper door.

Latching devices are provided on certain doors that are adapted to be actuated for locking said doors by the latching devices of other doors to permit of locking at least two doors in closed position with one lock. To accomplish this, I provide latching devices on one or more doors of the lockers, which are preferably the largest doors, such as the doors 15, 16, comprising a metal latch bar 21, which is, or may be, substantially rectangular in cross section, having one or more portions 22 formed away from the normal plane thereof to provide clearance for a bracket 23, which may be secured to the frame in any suitable manner, such as by rivets, or the like, and a pointed or V-shaped portion 24 for engagement in a correspondingly-shaped notch in the bracket 23 for latching the door. The bars 21 are secured to the frame by a plurality of shoulder rivets 25 extending through slots 26 in the bar. The size of the slots is determined by the depth of the V-shaped notch, in the bracket 23, being of sufficient length to permit the bar 21 to be raised or lowered to bring the point 24 into or out of interlocking engagement with the bracket 23.

While any suitable means may be provided for operating the bar 21, or locking said bar in a fixed position, I have shown a handle 27, which may be of any suitable form, and having portions 28 extending through slots 29 in the door, and an apertured portion 31. The portion 31 is preferably formed to extend below the handle. The length of the slots 29 is determined by the length of the slots 26 to permit full movement of the bar 21. A portion 32 of the door front is formed outward from the face thereof to embrace the apertured portion 31 of the handle 27, the portion 32 being apertured in alignment with apertured portion 31 and adapted to receive a locking device 33 which may be of any suitable type. A second latching device is provided for latching a hat locker door, which is adapted to be controlled by the latch bar 21. While this latching mechanism may be formed to control a plurality of doors, in the present embodiment I have shown the device controlling only one door.

A bar or rod 34, which is, or may be, round in cross section, is bent to form a slightly acute angle to provide a portion 35, of sufficient length to extend across the inside face of the locker front, and a portion 36 extending along one of the locker frame members 12, of sufficient length to extend approximately to the center of the door which it is to control. The portion 36 is preferably offset intermediate its ends, as at 37, to allow the portion thereof above the

offset to yield in a direction away from the door. The upper end of the portion 36 is preferably bent in toward the door opening and flattened to form a substantially rectangular portion 38. The rod 34 is sprung into position, an end thereof having a bearing in a flange 39 of the frame members, and the portion 36 thereof bearing against the inner side of a frame member 12 and being movable in a groove formed by a flange 41 of one of the wall sheets 13 and a web of the frame member 12. An angle plate 42 may be secured to each of the doors 13, 14 in any suitable manner, and a chamfered block 43 may be secured thereto and adapted for engagement by the portion 38 of the bar 34.

An angle plate 44 is preferably secured to the web of the frame member 12 (Fig. 6), which is also notched or cut away at 45 to provide clearance for the block 43. In operation, the latch bar 34 is held against endwise movement by the center dividing wall of the two locker compartments, which is secured between two flanges 39, and the slightly acute angle of this rod tends to maintain the portion 35 in a horizontal position, or parallel with the top of the door. In this position, the portion 38 of the rod is a sufficient distance above the path of the block 43 to permit the door to be opened freely. The rod 34 moves in this position when the lower door is opened. In closing the lower door, or the door 15 (Fig. 6), the bar 21 is raised to bring the V-shaped portion 24 above the bracket 23, and when so raised, a hook portion 46 of the bar 21 engages the rod 34, as shown, and downward movement of the bar 21, to latch the door 15, springs the rod 34 to the position shown in Fig. 6 with the portion 38 in the path of the block 43. If the door 14 be closed at this time, it is so latched or locked; and if the door be open at this time, upon closing the door, the chamfered block 43 wedges the portion 38 of the bar 34 backward away from the door until the block 43 has passed the portion 38, when this portion snaps in back of the block and locks the door. Upon locking the portion 31, of the handle 27, to the portion 32, of the door 15, by any suitable device, the doors 14, 15 are each secured thereby and in unlocking and opening the door, the door 14 is also unlocked and may be opened.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a locker unit, the combination of lower and upper locker compartments, separate doors closing each of said compartments, a latching device for one said door, including a latch bar, a resilient latching device for said other door arranged to normally assume door releasing position, said latch bar being arranged to cooperate with 10 the latching devices of both doors to lock said latching devices in closed position, and means for operating said latch bar to release said latching devices, said latching devices being arranged to permit latching 15 of one said door independently of said other door and latching of said other door when said first-mentioned door is in latched position.
2. In a locker unit provided with a lower 20 and an upper compartment, doors closing said compartments, latching means for each said door, said latching means including shiftable means supported by one said door and having locking engagement with the 25 latching means of said other door when said first-mentioned door is in closed position, means for manipulating said shiftable means, and means for locking said shiftable means against operation.
3. In a locker unit provided with a coat 30 compartment and a hat compartment arranged above said coat compartment, doors for closing said compartments, latching devices for each said door, said latching devices including shiftable means carried by said coat compartment door and controlling the latching device of said door and cooperating with the latching device of a hat compartment door to lock the latching device of said hat compartment door in door latching position when said coat compartment door is in closed position.
4. In a locker unit, a frame arranged to 45 provide an upper and lower compartment arranged in vertical relationship, doors closing each said compartment, latching devices for each said door, said latching devices including a shiftable latch bar and handle carried by the door of said lower compartment, said bar being arranged to operate the latching means of said lower door and having interlocking engagement with the latching device of said upper door when said lower door is in closed position.
5. In a locker unit, the combination of a 50 lower locker compartment and an upper locker compartment arranged over said lower compartment, separate doors closing said compartments, latching devices for each said door, said latching devices including an operable member carried by said lower door for operating a lower door latching device and having interlocking means for engaging an upper door latching device 60 when said lower door is in closed position,
6. In a locker unit, the combination of adjacent locker compartments, doors for each said compartment, latching devices for each said door, said latching devices including an operable member carried by one said door for operating the latching device of said door and having interlocking engagement with the latching device of said other door.
7. In a locking unit, the combination of adjacent locker compartments, doors for each said compartment, latching devices for each said door, said latching devices including an operable member carried by one said door for operating the latching device of said door and having interlocking engagement with the latching device of said other door to lock the same in door latching position when said first-mentioned door is in closed position.
8. In a locker unit, the combination of adjacent locker compartments, doors for each said compartment, latching devices for each said door, said latching devices including an operable member carried by one said door for operating the latching device of said door and having interlocking engagement with the latching device of said other door to lock the same in door latching position when said first-mentioned door is in closed position, said door latching device comprising resilient means adapted to assume door releasing position when disengaged from said operable member.
9. In a locker unit, the combination of adjacent locker compartments, doors for each said compartment, latching devices for each said door, said latching devices including an operable member carried by one said door for operating the latching device of said door and having interlocking engagement with the latching device of said other door to lock the same in door latching position when said first-mentioned door is in closed position, said door latching device comprising resilient means adapted to assume door releasing position when disengaged from said operable member and arranged to permit the latching of said door when in door latching position.
10. In a locker unit provided with adjacently arranged locker compartments, said compartments having separate doors, a latch bar operably mounted upon one said door adjacent a door opening and having a latch portion formed thereon for engagement with a latch keeper arranged in said compartment, a resilient door latching device for said other door having portions extending adjacent said latch bar and arranged normally to assume a door releasing position, said latch bar having a portion

adapted to engage and secure said resilient door latching device in door latching position when the door carrying said latch bar is in closed position, whereby both doors 5 may be simultaneously unlatched by shifting said latch bar.

11. In a locker unit, the combination of a frame providing lower adjacently arranged compartments and a plurality of superimposed compartments arranged above said adjacent lower compartments, doors for closing each said compartment, a shiftable latch bar arranged in each said lower compartment, means for operating each said shiftable bar, and a latching member for each said upper door comprising a resilient member mounted in said frame and having portions formed to provide separate door latches for each said upper compartment 10 adapted normally to assume door releasing position, said latch bars having a portion adapted to engage portions of said resilient latching member to secure said door latches in door latching position.

12. In a locker unit, the combination of a frame providing lower adjacently arranged compartments and a plurality of superimposed compartments arranged above said adjacent lower compartments, doors for closing each said compartment, a shiftable latch bar arranged in each said lower compartment, means for operating each said shiftable bar, and a latching member for each said upper door comprising a resilient member mounted in said frame and having portions formed to provide separate door latches for each said upper compartment, said latch bars having portions adapted to engage portions of said resilient latching 35 member to secure said door latches in door latching position.

13. In a locker unit, the combination of a frame providing lower adjacently arranged compartments and a plurality of superimposed compartments arranged above said adjacent lower compartments, doors for closing each said compartment, a shiftable latch bar carried by each said lower door, means for operating each said shiftable bar 45 and a latching member for each said upper door comprising a resilient member mounted in said frame and having portions formed to provide separate latches for each said upper compartment adapted normally to assume door releasing position, each said latch bar having portions adapted to engage portions of said resilient latching member when said lower doors are in closed position to secure said door latches in door 55 latching position.

14. In a locker unit, the combination of a frame providing lower adjacently arranged compartments and a pair of superimposed compartments arranged above said lower 65 compartments, doors for closing each said

compartment, a shiftable latch bar arranged on each of the doors of said lower compartments, means for operating each said shiftable bar, and a latching member for each said upper door comprising a resilient member mounted in said frame and having opposite portions each formed to provide a door latch for an upper compartment, said latch bars being each arranged to engage a portion of said resilient latching member to 70 secure a said latching member in door latching position, said resilient door latching means being adapted to be engaged and controlled by said latch bar to permit latching movement of said upper door when said latch bar is secured in door latching position.

15. In a locker unit, the combination of a frame providing lower adjacently arranged compartments and a pair of superimposed compartments arranged above said lower compartment, doors for closing each said compartment, a shiftable latch bar carried by each of said lower doors, means for operating each of said shiftable bars, and a latching member for each said upper door comprising a resilient member mounted in said frame and having opposite portions each formed to provide a door latch for an upper door, said latch bars each having portions adapted to engage a portion of said resilient latching member when said lower doors are in closed position to secure a said latching member in door latching position, said resilient door latching means having 95 latching construction and movement securing said upper doors when said latch bar is secured in latching position of the lower door.

16. In a locker unit, a door, a resilient door latching device, and means for securing said door latching device in door latching position, said resilient door latching device having latching means and construction for the latching of said door when said latching device is secured in door latching position.

17. In a locker unit provided with two lower compartments arranged side by side and two upper compartments arranged one above the other, doors for said compartments, a substantially vertically sliding latch bar arranged on each lower door, latching means for said lower doors including latching members carried by said bars and latching members for said upper doors comprising a resilient member having portions adapted to engage latch keepers carried by said upper doors, said portions being each connectable with a corresponding vertically disposed shiftable latch bar for the lower 120 doors.

18. In a locker, a frame comprising two lower locker compartments arranged side by side and two upper compartments arranged one over the other, doors for each of said 130

compartments and latching means for each of said lower doors, comprising a substantially vertically disposed shiftable latch bar mounted on the door and having portions 5 adapted to engage latch keepers arranged in said frame, a resilient rod mounted in said frame and having portions each engaging the upper end of one of said latch bars, the ends of said resilient rod extending respec- tively into each of said upper locker compartments and having latching portions each formed to engage a cooperating latch keeper arranged on a said upper door whereby the shifting of a latch bar will unlatch a lower door and the corresponding upper 15 door without unlatching the other upper door.

WALTER N. VANCE.
